UNITED STATES PATENT OFFICE

153,179

DESIGN FOR AN INKSTAND

Gustav J. Sengbusch, Milwaukee, Wis.

Application July 10, 1947, Serial No. 140,198

Term of patent 14 years

(Cl. D74—8)

To all whom it may concern:

Be it known that I, Gustav J. Sengbusch, a citizen of the United States, residing at Milwaukee, in the county of Milwaukee and State of Wisconsin, have invented a new, original, and ornamental Design for an Inkstand or the like, of which the following is a specification, reference being had to the accompanying drawings, forming part thereof.

Fig. 1 is a plan view, and

Figs. 2 and 3 are front and side elevations, respectively of an inkstand, showing my new design.

I claim:

The ornamental design for an inkstand or the like, substantially as shown,

GUSTAV J. SENGBUSCH.
